ATTORNEY.

UNITED STATES PATENT OFFICE.

DANIEL J. RYAN, OF CLEVELAND, OHIO.

APPARATUS FOR MAKING CORES.

Application filed October 28, 1922. Serial No. 597,668.

To all whom it may concern:

Be it known that I, DANIEL J. RYAN, a citizen of the United States, residing at Cleveland, in the county of Cuyahoga and State of Ohio, have invented certain new and useful Improvements in and Relating to Apparatus for Making Cores, of which the following is a specification.

My invention relates to apparatus for making cores for molds. More particularly, the invention has reference to a core box structure, capable of making a single core or a plurality of cores in a ready and economical manner.

The present invention is an improvement upon the apparatus disclosed and claimed in Patent Number 1,255,467, granted to me on the 5th day of February, 1918.

In making cup shaped articles, such as pistons, according to the apparatus disclosed in the aforesaid patent, the core box sections parted on diametrical lines extending from the open end of the core box to its inner end. This parting left a rib on the core, particularly where it had been in long use due to the wearing of the abutting walls of the sections. This rib in turn formed a seam or groove in the casting so that if the casting was subjected to strains, for example, that resulting from the engagement of a chuck with the walls of the piston to support it for grinding purposes, the piston would break or crack along this groove, thus indicating that the piston had been weakened thereby.

The object of the present invention is to overcome this disadvantage by so shaping the sections of each core box that the parting extends but a relatively short distance inwardly from the open end of the casting and then in other directions, thereby avoiding in the casting a groove which extends from end to end thereof and the weakness which would result thereby.

Another object of the invention is to provide a core box in which may be made in a rapid manner a core the walls of which serve to form a casting of great strength and durability.

Other objects of the invention will be apparent to those skilled in the art to which my invention relates from the following description taken in connection with the accompanying drawings, wherein—

Fig. 1 is a side elevation of a core box

structure embodying my invention and a machine constructed to support the core box structure and permit its manipulation, whereby the operations of making the cores and removing them may be facilitated.

Fig. 2 is a fragmentary view of the machine and a sectional view of the core box structure when ready to be filled with green sand or other suitable material which is to be used to form the cores.

Fig. 3 is a fragmentary top plan view of the parts shown in Fig. 2, with parts broken away.

Fig. 4 is a fragmentary view of the machine and a front elevational view of the core box structure after it has been filled with sand and tamped and ready to be inverted for a purpose to be later set forth.

Fig. 5 is a section through the core box structure as shown in Fig. 4, but on the line 5—5 of Fig. 3.

Fig. 6 is a section showing the operation of separating the cores and certain of the core box sections from the main sections of the core boxes.

Fig. 7 is a perspective view of the drag and the cores which have been formed, the core box sections for one core being entirely removed, one section of another core box being removed and the sections for one of the remaining cores being partly separated to show their manner of removal.

Fig. 8 is a fragmentary top plan view of a core and the subsections of a core box, the sub-sections being partly separated from the core.

Fig. 9 is a side view of the parts shown in Fig. 8.

Fig. 10 is a section on the line 10—10 of Fig. 8.

Fig. 11 is a section on the line 11—11 of Fig. 3.

Fig. 12 is a section on the line 12—12 of Fig. 3.

Fig. 13 is a section of a casting made in a mold the inner walls of which were formed by a core made upon the apparatus disclosed herein, the section being on the line 13—13 of Fig. 14.

Fig. 14 is a section on the line 14—14 of Fig. 13.

In the drawings, 1 indicates a machine adapted to support during the making of a core or cores, a core box structure, indicated as an entirety at 2. The machine 1

may be of any standard or preferred form and preferably constructed and adapted to facilitate the rapid and economical making of the core or cores.

5 The machine 1 is preferably provided with a bed 1^a, which, under the control of a lever 1^b (or other suitable mechanism) may be jolted to properly tamp the sand, as will be later set forth. The bed 1^a may be 10 mounted on trunnions 1^c, whereby the core box structure can be rolled over for a well known purpose.

1^d indicates a vertically movable carrier adapted to support the core or cores, after 15 they have been formed, and to lower them, whereby they will become disengaged from the core box frame or support. The carrier 1^d may be operated up and down by any suitable mechanism. The elevating and 20 lowering mechanism preferably comprises a coil spring 1^e, one end of which is connected to the frame of the machine 1 and its other end connected to the lever mechanism 1^f for the carrier 1^d. The spring 1^e is preferably 25 arranged to be placed under tension when the carrier 1^d is moved downwardly by the lever mechanism 1^f. The carrier 1^d may be actuated manually by means of a foot lever 1^g. As a result of this construction, the spring 1^e normally operates to lift 30 the carrier 1^d upon the release of a lock device which holds the carrier 1^d in its lowermost position.

It will be understood that the machine 1, 35 referred to and illustrated herein, in itself, forms no part of my present invention, but that it simply serves as a suitable support for the core box structure 2 and lends itself to the convenient and rapid operation thereof during the making of the cores.

The core box structure 2 comprises a core box frame 2^a and one part of a flask, 2^b, preferably the drag thereof, adapted to be detachably fixed to the core box frame 2^a 45 by suitable clamping devices 2^c. The core box frame 2^a is arranged to be fixed to the bed 1^a of the machine 1 in any well known way; it may be detachably fixed thereto in order that it can be removed when desired. 50 The core box frame 2^a comprises a plate 2^d mounted on top of the frame 2^a and formed with one or more openings 2^{a'} and core box receiving and supporting members 2^d (preferably cup shaped), one for each opening 2^{a'}. As shown in Figs. 2, 5 and 6, the open 55 ends of the receiving and supporting members 2^d register with the openings 2^{a'}. By preference, the cup shaped members 2^d are flanged, as shown at 2^{d'}, and the flanges 60 are secured to the underside of the plate 2^d by cap screws 2^x. The wall for each opening 2^{a'} is rabbeted, as shown at 2^{ax}, to form a seat for flanges on certain of the core box sections as will be later described.

65 3 indicates the core boxes, each remov-

ably mounted in one of the openings 2^{a'} and the receiving and supporting member 2^d correlated therewith. Each core box comprises a main section 3^a and a plurality of sub-sections 3^b adapted to form a

70

core of the desired size and shape when filled with sand and tamped. The main section 3^a comprises a cap or head 4 and a tubular body 5 which form the top and sides of the core. There are preferably two 75 sub-sections 3^b, each of semiannular shape and fit the outer end of the main section 3^a. Where the casting is to be provided with inwardly extended elements, for example, when the casting is a piston, indicated at A, having bosses on its inner walls 80 provide therefor in the core box sections in the following manner: The main section 3^a of each core box is cut away as shown in 5^a on diametrically opposite sides 85 and each sub-section 3^b is provided with an extension 6 shaped to fit the adjacent cut away portion 5^a and a laterally projecting member 6^a which forms a recess a in the 90 side of the core. The extension 6 is arranged midway between the ends of the adjacent sub-section 3^b. As a result of this arrangement, the sub-sections, when being separated from the core (see Figs. 7, 8, 9 and 10), are moved away from each other 95 in a direction parallel to or in a line coincident with the axes of the boss forming recesses a. From the foregoing description it

95

will be seen that the parting between the core box section extends downwardly from 100 the base of the core a relatively short distance, equal to the thickness of the sub-sections 3^b, and then circumferentially in either direction towards the boss forming recesses, then around these recesses. In the preferred form of construction, the sub-sections 3^b extend inwardly beyond the end wall of the main section 3^a as shown at 3^{b'}, to form an angular groove 3^c in the core, 105 which groove provides a collar 3^d in the casting. By this arrangement the parting is effected along the underside of the collar forming groove and hence eliminates the formation of a rib on the core and the 110 resulting disadvantages that would be incident thereto. In practice I have found that by arranging the parting walls of the core box section so that they extend along or coincident (1) with the lower edge of the thickened wall which forms a collar in the casting at or adjacent its outer end and (2) with the line of jointure for the bosses and piston skirt, the formation of a seam or 115 groove in the casting is done away with or eliminated, except at the points where the outer ends of the sub-sections abut, but as this parting extends only a relatively short distance inwardly from the open end of the casting, the latter is not weakened.

115

120 In actual practice, the core box frame 2^a 130

is provided with one or more receiving members 2^a, each adapted to receive a core box 3 which is capable of forming a core for the largest sized piston or other device which 5 the structure 2 may at any time be called upon to make. By this construction I am enabled to insert in the receiving members 2^a core boxes 3 of varying internal sizes to form cores of any desired diameter and 10 shape within the capacity of the structure.

In the drawings I have illustrated a core box for making a core for a piston casting of relatively small size. In this illustrated 15 form of construction, the main section 3^a is provided with a head 7 which occupies the space between its cap 4 and the bottom or end wall 8 of the receiving and supporting member 2^a, the head preferably being secured to the end wall 8 by a screw 9.

20 In the core box frame 2^a herein illustrated I have adapted my invention to the making of four cores simultaneously. It will be understood, in this connection, that such frame may be arranged to form a greater 25 or less number of cores. Furthermore, since each core box 3 is insertible and removable independently of the remaining core boxes, I am enabled to form a plurality of cores 30 of similar size or to make them of different sizes.

10 indicates a suitable shaped pattern, preferably fixed to the frame plate 2^c, to form a central metal receiving basin and gates leading therefrom, as will be readily 25 understood by those skilled in the art to which my invention relates.

In operation, the core box frame 2^a is arranged in horizontal position with the desired sized core boxes 3 positioned in the receiving members 2^a thereof. The drag 2^b is mounted on the frame 2^a, the pins 2^c on the plate 2^c fitting the openings formed in lugs 2^b on the drag 2^b, thus causing the drag 40 to be properly positioned. Green sand is then placed in the core boxes and drag and tamped in any well known manner, after 45 which the sand is leveled and a cover or mold board 11 placed over and secured to the drag 2^b by a member, which forms one 50 element of the clamping devices 2^c. (See Fig. 4.) The board 11 may be formed with openings 12 through which a vent forming pin may be inserted to form vents B 55 (see Fig. 5). The core box structure 2 is rolled over and the carrier 1^a elevated until it engages the cover board 11. Upon the release of the clamp devices 2^c, the carrier is 60 allowed to drop or move downwardly, the cover board 11, drag 2^b, and core box sections 3^b, with the cores formed within them, moving downwardly from the frame 2^c and supporting members 2^a with the carrier 1^a under the influence of gravity. The core box sections 3^b of each core box are then 65 disengaged from the cores by movement later-

ally away from each other, as by the hands of the molder or in any other suitable manner. In such operation, both sections 3^b are preferably moved simultaneously in opposite directions or radially of the axis of the 70 core. If desired, the drag 2^b and core boxes 3 with the cores may be transported from the carrier to an auxiliary support or table where the core box sections can be readily removed. The drag 2^b carrying the cores 75 may be placed in position to have the cope (not shown) fastened to it preparatory to pouring.

In the construction herein shown it is desirable to have the core boxes arranged so 80 that upon the disengagement of the cores and sub-sections from the main sections, the sub-sections will be arranged to permit their ready removal or separation. I attain this result by securing the main sections in fixed 85 relationship, preferably by means indicated at 13, acting supplemental to the screws 9, to secure them to the receiving and supporting members 2^a to insure the proper positioning of the sub-sections in the successive 90 operations of making and removing the cores. The means 13 chosen herein for illustrative purposes comprises dowel pins, each extending through an opening in the end wall 8 into a recess 14 formed in the adjacent 95 head 7.

With my invention it is possible to use green sand in the making of cores and to insure that the cores will be properly positioned in the cope of a flask without any 100 skill being required on the part of the molder or operative to secure this highly advantageous result. Thus the labor, equipment, time and expense of baking the cores and later positioning them in the flask is 105 obviated, while on the other hand the green sand can be used over and over for making new cores.

In the construction herein disclosed, it 110 will be seen that I am able to make pistons or piston castings in which walls having seams or grooves formed in them incident to the formation of ribs on the core resulting from the wear of the abutting walls of the core box sections, are eliminated. As a 115 result, the piston walls are of uniform thickness and may be accurately ground to the desired size without danger of breakage or strain. Furthermore, by the use of my invention I am able to provide cores for use 120 in molds wherein castings having relatively thin walls may be made and ground to proper size, thereby producing pistons of relatively light weight and capable of long use.

To those skilled in the art of making apparatus of the class described, many alterations in construction and widely differing embodiments and applications of my invention 125 will suggest themselves, without de-

parting from the spirit and scope thereof. My disclosures and the description herein are purely illustrative, and are not intended to be in any sense limiting.

5. What I claim is:

1. In apparatus of the class described, the combination of a support and a core box comprising a main section of tubular shape having a cut away portion extending inwardly from its open end and a sub-section engaging the outer end of said main section and provided with an extension fitting said cut away portion and shaped to form a boss forming recess in the core.

10 2. In apparatus of the class described, the combination of a support, and a core box for making cores for cup shaped molds, said box comprising a main section of tubular shape having cut away portions extending inwardly from its open end and sub-sections each provided with an extension, each sub-section engaging the outer end of the main section and its extension fitting the adjacent cut away portion therein and arranged to 20 form a boss forming recess in the core.

25 3. In apparatus of the class described, the combination of a support, and a core box for making cores of cup shaped molds, said box comprising a main section of tubular shape having cut away portions extending inwardly from its open end and sub-sections each of semi-annular shape and provided with an extension, each sub-section engaging the outer end of the main section and its 30 extension fitting the adjacent cut away portion therein and arranged to form a boss forming recess in the core.

40 4. In apparatus of the class described, the combination of a support, a core box for making cores for cup shaped molds, said box comprising a main section of tubular shape having cut away portions extending inwardly from its open end and sub-sections each provided with an extension, each sub-section engaging the outer end of the main section and its extension fitting the adjacent cut away portion therein and arranged to 45 form a boss forming recess in the core, and means for securing the main section in said 50 support.

55 5. In apparatus of the class described, the combination of a support, and a sectional core box mounted therein and arranged to form a core for a cup shaped casting having internal bosses, said box comprising a main section of tubular shape and a pair of semi-annular sub-sections engaging the outer circumferential end of said main section and each provided with an extension to form a 60 boss forming recess in the core, said main section being formed with cut away portions to receive said extensions, whereby the parting is extended from the abutting ends of said sub-sections in a direction circumferentially of the core to the boss forming re-

cesses and around the latter along the line where in the casting the bosses are joined to the wall of the latter.

6. In apparatus of the class described, the combination of a support comprising a plate 70 having a plurality of rabbeted openings and receiving members each associated with one of said openings, of a plurality of sectional core boxes each engaging the walls of one of said openings and the receiving member associated therewith, each core box comprising a main section of tubular shape having cut away portions extending inwardly from its outer end and sub-sections engaging said main section and provided with extensions 75 fitting the cut away portions therein.

7. In apparatus of the class described, the combination of a support comprising a plate having a plurality of rabbeted openings and receiving members each associated with one of said openings, of a plurality of sectional core boxes each engaging the walls of one of said openings and the receiving member associated therewith, each core box comprising a main section of tubular shape having cut 80 away portions extending inwardly from its outer end and sub-sections engaging said main section and provided with extensions 85 fitting the cut away portions therein, said sub-sections being separable from said plate, receiving member and main section and movable with the core.

8. In apparatus of the class described, the combination of a support, and a core box 90 for making cores for cup shaped molds, said box comprising a main section of tubular shape having cut away portions extending inwardly from its open end and sub-sections separable from said main section and from each other, each sub-section engaging the 95 outer end of the main section and provided with an extension fitting the adjacent cut away portion therein and arranged to form a boss forming recess in the core.

9. In apparatus of the class described, the combination of a support, and a core box 100 for making cores for cup shaped molds, said box comprising a main section of tubular shape having cut away portions extending inwardly from its open end and sub-sections each of semi-annular shape and provided with an extension, each sub-section 105 engaging the outer end of the main section and its extension fitting the adjacent cut away portion therein and arranged to form a boss forming recess in the core, and portions of each sub-section and its extension projecting inwardly beyond the wall of the main section.

10. In apparatus for making cores for 110 piston castings having internal bosses and an internal collar around its open end, the combination of a support, and a core box mounted therein and comprising a plurality 115 of separable sections adapted to be assem- 120 125 130

bled in said support and having their abutting walls extending along the inner edge of the groove which forms said collar between the boss forming recesses and around the latter.

11. In apparatus for making cores for piston castings having internal bosses and an internal collar around its open end, the combination of a support, a core box mounted therein and comprising a plurality of separable sections adapted to be assembled in said support and having their abutting walls extending along the inner edge of the groove which forms said collar between the boss forming recesses and around the latter.

12. In apparatus of the class described, the combination of a support, a core box comprising a main section of hollow shape having a cut-away extending inwardly from its open end and a sub-section engaging the outer end of said main section and having an extension corresponding in shape to and fitting said cut-away, and a member extend-

ing laterally from the inner end of said extension.

13. In apparatus of the class described, the combination of a support, and a core box mounted therein, said box comprising an inner, hollow non-sectional portion having a cut-away extending inwardly from its outer end and an outer portion comprising separable sections one of which has an extension corresponding in shape to and fitting said cut-away.

14. In apparatus of the class described, the combination of a support, and a core box mounted therein, said box comprising an inner, hollow non-sectional portion having cut-aways extending inwardly from its outer end and an outer portion comprising separable sections each having between its side edges an extension corresponding in shape to one of said cut-aways and fitting therein.

In testimony whereof I have hereunto subscribed my name.

DANIEL J. RYAN.
